(57) **CLAIM**

The ornamental design for a lever handle, as shown and described.

DESCRIPTION

FIG. 1 is a perspective view of the new design for a lever handle;

FIG. 2 is a front elevational view of the new design for a

lever handle, the rear elevational view being a mirror image;

FIG. 3 is a top plan view of the new design for a lever

handle;

FIG. 4 is a bottom plan view of the new design for a lever

handle;

FIG. 5 is a right side elevational view of the new design for

a lever handle; and,

FIG. 6 is a left side elevational view of the new design for

a lever handle.
